COVE STRIP

Ralph Corson, Arlington, N. J., assignor to Congoleum-Nairn Inc., a corporation of New York

Application December 24, 1949, Serial No. 134,947

5 Claims. (Cl. 20—74)

1

This invention relates to an improved cove strip adapted for use in connection with the installation of flexible smooth surface coverings as a support therefor at the juncture between angularly disposed surfaces of structural members to which the covering is applied.

When installing a flexible smooth surface covering such as a linoleum floor covering or the like, it is the practice in many cases to employ a curved molding or cove strip under the floor covering where the floor and the base of the walls meet in order that the floor covering can be laid in a manner which will provide uniformly rounded or coved corners. Likewise a cove strip frequently has been similarly employed underneath linoleum wall coverings or the like at intersecting wall surfaces. Conventional cove strips for such purposes are made either of wood or of plastic materials. Such conventional cove strips have presented a number of difficulties such as excessive susceptibility to warping, chipping and splitting, and to distortion in packaging, shipment and installation, as well as lack of resistance to moisture and temperature changes. Moreover, conventional wooden-type cove strips do not readily conform to surface irregularities such as are commonly encountered in floors or walls and to differences in the angle at which such surfaces are disposed. In the installation of such conventional type cove strips the cutting, squaring and mitering required for proper installation demand special skills on the part of the workmen. Especially in the case of conventional plastic type cove strips that are made by extrusion methods, the product is relatively fragile and subject to rupture or distortion.

It is an object of this invention to provide a cove strip whereby the above-mentioned difficulties may be successfully overcome. It is one of the objects and advantages of this invention to provide a cove strip which can be produced very economically and which is extremely easy to install without requiring the employment of special skills or special tools during installation. It is a further object and advantage of this invention to provide a cove strip which is flexible and resilient and which at the same time is extremely tough and is capable of withstanding rough handling during packaging and shipment and during installation. It is a further object and advantage of this invention to provide a cove strip which is highly resistant to moisture and to temperature changes, which is not susceptible to splitting, cracking or chipping, and which can be readily held in place by any type of securing means such

2

as brads, adhesives, or the like. It is a further object of this invention to provide as an article of manufacture a cove unit comprising a cove strip of the character mentioned in integral relation with a covering material presenting a decorative surface.

According to the principal feature of this invention, the improved cove strip is made from a plurality of ribbons of different widths of flexible material having substantial stiffness such, for example, as a felted fiber sheet impregnated with a suitable binder. The ribbons are oriented lengthwise in a pile of V-shaped cross section which is closed by an external concave surface presented by one of the ribbons. In order to provide structural integrity, the respective ribbons as oriented lengthwise in the pile of V-shaped cross section are secured together along the longitudinal dimension of the strip. Preferably, the securement together of the ribbons in the pile is at or close to the centers of each of the strips, the centers being arranged in substantially overlying relation and the portions of the respective strips adjacent the margin thereof being left free and unsecured together, thereby permitting the margins of the individual ribbons to conform to the surfaces against which the cove strip is to be placed while at the same time providing a cove strip which is strong and tough and which likewise is extremely flexible. If desired, a cove unit may be afforded by securing to the cove strip in face-to-face relation with the ribbon at the wider extremity of the pile a sheet of covering material presenting a decorative surface.

Further purposes, advantages and features of this invention will be apparent from the following description of a typical embodiment of this invention and a typical installation thereof in connection with the accompanying drawings, 40 wherein

Fig. 1 is a sectional elevation of a cove strip embodying this invention as installed to provide a coved support for a flexible smooth surface covering at the juncture between a floor and a wall; 45 Fig. 2 is an end view of the cove strip shown in Fig. 1 on a larger scale;

Fig. 3 is a plan view of a portion of the cove strip shown in Figs. 1 and 2;

Fig. 4 is a sectional view of the cove strip shown in Fig. 3 taken along the line 4—4 of Fig. 3; and

Fig. 5 is similar to Fig. 2 showing the cove strip of Fig. 2 produced as an article of manufacture with a sheet of decorative covering material secured to the concave surface presented by the cove strip.

In Fig. 1 the cove strip which embodies the present invention is indicated generally by the reference character 10 and is shown as installed at the corner between the floor 11 and the wall 12. A flexible smooth surface covering such as a conventional linoleum type floor covering is indicated by the reference character 13. This covering extends along the floor and extends a short distance up the surface of the wall 12. Both the cove strip 10 and the covering 13 may be secured in place by a suitable adhesive, not shown. At the upper margin of the covering 13 there is shown a finishing strip 14 which may be made of metal and which may or may not be employed depending upon the type of installation. It is to be noted that the cove strip 10 provides a concave or coved surface which supports the covering 13 so that at the juncture between the floor 11 and the wall 12 the covering 13 presents a continuous rounded surface. Such an installation is typical when a cove strip is employed and is widely used in linoleum installation practice in order to avoid dirt-catching corners at the juncture between the floor and the wall, and in order to eliminate any cracks or discontinuities at the juncture between the floor and the wall.

The improved cove strip of this invention is shown in greater detail in Figs. 2, 3 and 4. In the particular embodiment shown the cove strip consists of seven ribbons of flexible sheet material, these ribbons being indicated by the reference characters 15, 16, 17, 18, 19, 20 and 21. The respective ribbons as shown are oriented lengthwise with their centers substantially overlying and with the different widths arranged so that the assembly has a V-shaped cross section closed by the concave exterior surface of the ribbon 15. The ribbons are secured together approximately at the centers thereof by the stitches 22 which are disposed along the longitudinal extent of the cove strip and which preferably are in the form of wire stitches, using a flat wire for the purpose. However, the stitching may be carried out using a fibrous cord for the purpose or the ribbons may be secured together by means of staples or by use of an adhesive.

In Fig. 5 an article of manufacture is shown wherein the cove strip 10, as shown in Figs. 1 to 4 and described hereinabove, has preformed therewith a sheet 23 of covering material presenting a decorative exposed surface. The sheet 23 may, for example, be a sheet of linoleum covering material which is permanently secured face-to-face with the concave surface of the ribbon 15 as by use of an adhesive, although any other securing means may be employed. In a linoleum installation it frequently is desirable to provide at the intersection of the floor and a wall a strip of material having the general appearance of a base board. The cove unit such as that shown in Fig. 5 is suitable for the purpose and is highly desirable in that it provides a coved lower portion and an upper portion which extends a short distance up the wall. The covering material comprised in the cove unit may, if desired, be of a color contrasting with the color of the floor and wall coverings. The cove unit shown in Fig. 5 can be readily produced at the plant and can be readily and accurately installed in a single operation, this obviating the necessity for first installing a cove strip and thereafter cutting a strip of desired width and accurately putting it in place, i. e., operations requiring much more time and requiring the employment of more high-

ly skilled workmen. The article shown in Fig. 5, can be varied in obvious ways. For example, the sheet 23 of covering material, instead of having greater extent on one side of the cove strip backing than on the other side, may extend approximately equally on each side of the cove strip backing, and such construction would normally be employed when the cove unit is to be installed along the angle between intersecting walls.

The cove strip of this invention can be produced very readily. Thus, all that is required is to cut some suitable flexible sheet material into ribbons of different widths and to assemble them in a pile wherein they are oriented lengthwise and arranged so as to be generally of successively narrower widths. Thereupon the ribbons can be secured together by the stitching or other suitable securing means, and by subjecting the assembly to pressure against a mold of appropriate conformation for providing the desired radius for the coved surface of the support.

Any suitable sheet material can be used in making the cove strip of this invention. Because of its low cost, as well as its all-round suitability for the purposes of this invention, a felted fiber sheet material is employed which is impregnated with a suitable binder. The felt may be composed of any suitable fiber or mixture of fibers either organic or mineral, e. g., fibers such as those conventionally used in the manufacture of flooring felt, building paper or the like. The binder that is ordinarily employed is a bituminous binder such as an asphalt having a softening point of the order of 150° F. to 190° F., and the felted fiber sheet may be impregnated to any suitable extent with the binder, e. g., so that the felted fibers and the binder are approximately in equal proportion by weight. Other binders may also be employed such as resins or oleo-resinous binders or pitches, e. g., cotton-seed pitch, of the type disclosed in Patent No. 2,432,185. Vulcanized rubber may also be employed. It is usually desirable to employ a binder which is of the thermoplastic type, e. g., a suitable asphalt or other bitumen, so that the shaping of the cove strip to the desired radius of curvature may be facilitated by the application of heat during the pressure formation and so that when the shaped cove strip has been permitted to cool it will tend to retain the desired radius of curvature.

In addition to impregnated felt materials, other sheet materials may be used such as a woven fabric which has been impregnated with a binder such as those mentioned above in order to enhance its toughness and stiffness as well as to enhance its resistance to moisture and other deteriorating influences. Other sheet materials such as sheets of vulcanized rubber also may be used to afford the ribbons comprised in the improved cove strip.

The dimensions of the ribbons will, of course, depend upon the size of the cove strip that is desired and upon the radius of curvature of the concave surface to be presented thereby. Generally, the ribbons are composed of sheet material which is ordinarily .04 inch in thickness but it may, of course, be varied in thickness depending on the materials available and the overall size of the cove strip. Generally, the sheet material for the ribbons runs between about .02 inch and .06 inch in thickness. In order to build up the desired backing for the ribbon which presents the concave external surface so as to obtain a pile of V-shaped cross section, the respective

strips generally differ in width by increments of the order of $\frac{1}{4}$ inch to $\frac{3}{8}$ inch. The particular embodiment shown in the drawings is illustrative of a cove strip wherein the ribbon intended to present the external concave surface is about 2 inches in width and wherein the narrowest ribbon is of the order of $\frac{3}{8}$ inch in width. When these ribbons are arranged so that the widths differ by increments of the order above mentioned, a satisfactory cove strip is provided when seven ribbons are employed in the pile. However, for larger cove strips an additional number of ribbons would ordinarily be employed depending upon the relative thicknesses thereof, and for a narrower cove strip a lesser number of ribbons would be employed.

The individual ribbons preferably have substantial stiffness while at the same time being flexible. The stiffness and flexibility of asphalt-impregnated felt of the character above described are well suited for the practice of this invention inasmuch as a cove strip made from ribbons of such material according to this invention provides the desired properties of being readily flexed and conformed to surfaces against which it may be placed while affording a coved support that is rugged and strong when installed. Ribbons composed of extremely flexible materials such as very thin unimpregnated fabrics are not ordinarily as suitable as fabrics of the order of thickness above mentioned which are impregnated with a bituminous or similar binder. On the other hand, ribbons that are very hard and rigid such as composed of a fabric highly impregnated with a very hard, brittle binder do not afford the desired flexibility and capacity to be readily conformed to surfaces against which the strip is placed. Thus, if a binder is employed which normally is of the hard and brittle type, the binder should be effectively plasticized using known plasticizers for the purpose. If the binder employed is not of the thermoplastic type but is adapted to permanently become of greater strength and stiffness as the result of such influences as solvent evaporation, oxidation, thermosetting or the like, the cove strip can be shaped to afford the desired curvature for the coved surface while the binder is still soft, the binder thereafter becoming of increased hardness and toughness due to influences such as those mentioned thereby causing the cove strip to assume its ultimate stiffness and strength when the cove strip is in its finished shape so that the finished shape will be permanently retained.

For most purposes the ribbons in the pile are of such number and dimensions that when the desired radius of curvature for the cove is afforded, the longitudinal margins of the respective strips will fall along planes intersecting at approximately a right angle. In other words, the angle of V of the ribbons as arranged in a pile of V-shaped cross section is approximately 90° . However, it is usually preferable in constructing the improved cove strip to have the ribbons dimensioned so that when the cove strip is placed along the angle between the planes intersecting at a right angle, the margins of the ribbons, particularly the wider ribbons, will have a slight amount of clearance therebetween, as shown in Fig. 2. Thus, if the angle between the planes were to be slightly greater than 90° , the margins of the ribbons can still be disposed in contact with the surfaces of the intersecting planes since these margins are free to be brought somewhat closer together, thus accommodating

them to the larger angle. Similarly, if the angle between the planes is somewhat smaller than 90° , the margins of the respective ribbons can become slightly more separated from each other, thus accommodating them to the smaller angle. Moreover, this attribute of the cove strip whereby it can accommodate itself to larger or smaller angles between intersecting planes also is of great utility in permitting the cove strip to accommodate itself to irregularities in the surfaces against which it is placed. Thus, it is seen to be a very desirable feature of the cove strip of this invention that it be made by employing a plurality of ribbons which are free and not secured to each other adjacent the margins thereof. This construction also affords very great flexibility combined with toughness in the cove strip as a whole so that it can be readily handled and packaged for shipment without injury due to rough treatment and so that it not only can be readily installed and conformed to the surfaces against which it is to be placed, but also can be thus installed and conformed without special shaping or risk of injury.

While the cove strip as hereinabove described and illustrated in the accompanying drawings wherein the cove strip is composed of ribbons which are shaped to the desired curvature and largely or entirely retain such curvature, constitutes preferred practice of this invention, the ribbons of the cove strip as made up prior to installation may have substantially less curvature than that assumed by the ribbons when the cove strip is installed in place or may even be substantially flat prior to installation. In any such case, however, the number and dimensions of the respective ribbons should be such that the marginal edges thereof, when the cove strip is installed, will fall at least approximately in planes corresponding to the surfaces presented at the angle between an intersecting floor and wall or between intersecting walls. If the ribbons prior to installation of the cove strip do not have the curvature assumed after installation, it is preferable that the ribbons be composed of material that can be readily flexed during installation. Thus if bituminized felt of the character mentioned hereinabove is used, it is preferable that the ribbons be made relatively thin, e. g., $.02''$ to $.03''$ in thickness and that a greater number be used as compared with the embodiment shown in the drawings. Moreover, the ribbon whose surface closes the V of the cove strip as installed, while preferably presenting the concave contour desired for the covering to be applied thereto, may approach such concave contour only approximately, any discrepancy in this regard being counteracted by the inherent stiffness of the covering that is applied thereupon and by the adhesive used to bond it in place.

In securing the cove strip in place, any conventional means for doing so may be employed. Thus, the cove strip of this invention may be secured in place by means of a suitable adhesive such as that used in adhesively bonding flexible smooth surface coverings to floors and walls. If desired, the cove strip can be secured in place by means of brads, nails, or the like, and it is an important advantage of the cove strip of this invention that it is not subject to cracking, splitting, chipping, or the like during handling and installation, whether nails, brads, or the like or other securing means are used. Due to the peculiar construction of the cove strip of this invention, it can be readily cut using shears or

a knife for the purpose, and without requiring any special skills or any special tools for cutting or shaping the cove strip so as to accommodate it to the surfaces against which it is to be used, including operations such as squaring and mitering. Likewise, due to the construction of the improved cove strip of this invention, it is not seriously affected by atmospheric or temperature changes or as the result of moisture. The improved cove strip is very light in weight and can be readily packaged and shipped. It also maintains its shape during shipment and handling and is extremely tough and resistant to injury.

While this invention has been described in connection with a typical embodiment thereof, it is to be understood that this has been done for the purpose of affording a better understanding of this invention and of the practice thereof. However, the typical preferred construction which has been described is merely illustrative of the practice of this invention, inasmuch as cove strips embodying this invention may be varied from the form and construction shown while utilizing the features of novelty which characterize the improved cove strip of this invention.

I claim:

1. As an article of manufacture a preformed elongated cove unit comprising a pile of ribbons of different widths of flexible material which are oriented lengthwise and which are secured together along the longitudinal dimension of the unit with opposed marginal surfaces of said ribbons separable and portions of said ribbons adjacent the margin thereof capable of individual flexure, said cove unit being adapted for placement along the intersection between planes intersecting at approximately a right angle and when so placed having a generally V-shaped cross section.

2. As an article of manufacture a preformed elongated cove unit comprising a pile of ribbons

of successively diminishing widths of flexible material having substantial stiffness, which ribbons are oriented lengthwise with their centers substantially overlying and secured together solely in the region of the approximate centers thereof leaving free those portions of the opposed surfaces of the ribbons adjacent the margins thereof, said cove unit being adapted for placement along the angle between planes intersecting at approximately a right angle with the margins of said ribbons substantially in contact with said planes, and when so placed the ribbon at the wider extremity of the pile providing a substantially concave surface.

15 3. As an article of manufacture a preformed elongated cove unit according to claim 2 wherein said ribbons are ribbons of impregnated fibrous sheet material.

20 4. As an article of manufacture a preformed elongated cove unit according to claim 2 wherein said ribbons are secured together solely by stitching disposed substantially along the center line of the respective ribbons.

25 5. As an article of manufacture a preformed elongated cove unit according to claim 2 wherein a sheet of covering material presenting a decorative exterior surface is secured to said pile face to face with the ribbon at the wider extremity of the pile and in conformity with the concave curvature thereof.

RALPH CORSON.
